UNITED STATES PATENT OFFICE.

MONTFORT STOKES JONES, OF SHREVEPORT, LOUISIANA, ASSIGNOR OF
ONE-HALF TO SAMUEL N. FORD, TRUSTEE, OF SAME PLACE.

DESIGN FOR A SOCIETY-EMBLEM.

SPECIFICATION forming part of Design No. 19,862, dated May 27, 1890.

Application filed February 27, 1890. Serial No. 342,016. Term of patent 14 years.

To all whom it may concern:

Be it known that I, MONTFORT STOKES JONES, a citizen of the United States, residing at Shreveport, Caddo parish, Louisiana, have 5 invented certain new and useful Improvements in Designs for Society-Emblems, of which the following is a specification.

In the accompanying drawing is shown an illustration of my design.

10 The design consists of an emblem representing the head of a deer or elk having spread horns *B B* and antlers *a a*.

The leading feature of the design is the head having a peculiar arrangement of the 15 antlers to form letters of the alphabet, constituting a name or the initials of a name,

such as the initials B. P. O. E. Around the neck is represented a band or belt *b*, supporting a medallion *c*.

The said emblem may be used in various 20 connections, such as badges, cuff-buttons, scarf-pins, seals, &c.

What I claim is—

The design for a society-emblem herein shown and described. 25

In testimony whereof I have signed my name to this specification in the presence of two subscribing witnesses.

MONTFORT STOKES JONES.

Witnesses:

J. B. BEATTIE,
P. B. WEAKS.
